UNITED STATES PATENT OFFICE.

ALFRED N. ALTEMUS, OF PHILADELPHIA, PENNSYLVANIA, ASSIGNOR TO JACOB K. ALTEMUS, OF PHILADELPHIA, PENNSYLVANIA.

YARN-WINDING MACHINE.

Application filed November 21, 1923. Serial No. 675,993.

To all whom it may concern:

Be it known that I, ALFRED N. ALTEMUS, a citizen of the United States, residing at Philadelphia, in the county of Philadelphia and State of Pennsylvania, have invented certain new and useful Improvements in Yarn-Winding Machines, of which the following is a specification.

This invention relates to improvements in yarn winding machines wherein are employed a vertically arranged winding spindle, a driving wheel, and a whirl disc which is adapted to rest upon and be driven by the driving wheel and which is slidably engaged with the spindle and provided with means to cause the spindle to be rotated with the disc and to permit the disc to be raised and lowered from and into driving engagement with the driving wheel and to rise and fall under the irregularities of the driving wheel while being driven thereby without raising or lowering the spindle.

An object of my invention is to provide an inexpensive, novel and efficient means for raising and lowering the whirl disc from and into driving engagement with the driving wheel to stop and start the actuation of the winding spindle by the operation of a hand operated lever; and a further object of my invention is to construct and arrange the hand operated lever and its associated parts so that the part which supports the whirl disc when it is raised from engagement with the driving wheel will be moved very slowly relatively to the movement of the hand operated lever which moves it during the initial movement of the lever while the whirl disc is being engaged with the driving wheel, and thereafter will be moved faster relatively to the movement of the lever while the said part is being moved from the whirl disc to provide a clearance between the part and the disc to permit the disc to rise and fall under irregularities in the driving wheel while the disc is being rotated thereby, and thus reduce the yarn breakage heretofore caused by the too rapid starting of the winding spindle when the whirl disc was engaged with the driving wheel.

In the accompanying drawings illustrating my invention,

Figure 1 is an elevation of a portion of a yarn winding machine embodying my invention.

Figure 2 is a front view, partly in section of the parts shown in Fig. 1.

Figure 3 is a horizontal section on line 3—3 of Fig. 1.

Figure 4 is a view similar to Fig. 1, 60 showing a modified form of embodiment of the invention.

Figure 5 is a vertical section on line 5—5 of Fig. 4.

Referring to the drawings, the main supporting frame of the machine includes in its construction a table 2 and a bracket 4 suitably secured thereon. The bracket 4 is provided with upper and lower forwardly projecting arms 6 and 7 carrying spaced 70 bearings 8 and 9, respectively. The winding spindle 10 is journaled in and extends between and above the bearings 8 and 9, and it is free to rotate therein. Vertical movement of the spindle 10 is prevented by 75 collars 11 and 12 secured thereto and adapted to engage the top and bottom of the lower bearing 9, respectively.

The upper portion of the spindle 10 is adapted to receive and rotate a cone or 80 other suitable foundation for the yarn package to be wound in the usual well known manner, and the spindle 10 carries a disc or collar 13 to receive the base of the cone or other foundation.

The collar 11 is made square in cross section and it extends into a corresponding opening in a whirl disc 14 which surrounds the spindle 10. The disc 14 has an upwardly extending sleeve 15 formed thereon 90 and having an annular groove 16 in the upper portion thereof providing an annular flange 17 hereinafter referred to. The disc 14 and its sleeve 15 are slideable vertically on the spindle 10 and collar 11, and the engagement of the disc 14 with the collar 11 causes the spindle 10 to be rotated with the disc 14 when it is rotated, and permits the disc to be raised and lowered without raising and lowering the spindle.

The whirl disc 14 rests normally upon the leather covering 18 secured on the periphery of a driving wheel 19 which is carried by a shaft (not shown) journaled in bearings (not shown) on the machine frame 105 and it is driven thereby in the usual manner well known to persons skilled in this art. While the disc 14 is resting upon the covering 18 of the driving wheel 19 and being driven thereby, the disc rises and falls 110

- slightly, due to irregularities in the leather covering 18 and due to the uneven wearing of the covering. The up and down movements of the disc 14 due to the irregularities in the leather covering 18 do not raise or lower the spindle 10, thus ensuring an even and uniform winding of the yarn upon the cone carried by the spindle and the prevention of accidental underwinding.
- 10 Referring now to Figs. 1, 2 and 3 of the drawings, a lever 20 is fulcrumed, at 21, on one side of the upper bearing 8 and it is provided with an upwardly extending arm 22 and a forwardly extending arm 23 having a suitable handle 24 formed on the forward end thereof by means of which the lever may be raised and lowered.
- 15 A part or arm 25 has its upper end portion pivoted, at 26, to the upper end portion 20 of the lever arm 22. The part 25 extends downwardly from the lever arm 22 to a position adjacent to one side of the sleeve 15 of the whirl disc 14 and it has a pin 27 secured to its lower end portion. The pin 27 25 extends from the part 25 inwardly through and beyond a vertical slot in a fixed arm 28 which is formed on and extends downwardly from the upper bearing 8. The lever 20 rests normally upon a projection or stop 29 30 formed on the bearing 8, as shown by full lines in Figs. 1 and 2, and, when the lever 20 is raised from its normal position to the position shown by dot-and-dash lines in Figs. 1 and 2 and then returned to its normal 35 position, the part 25 and pin 27 will be raised and lowered thereby. The side walls of the slot in the part 28 guide the pin and cause it to move vertically and permit it to act as a pivot for the lower end portion 40 of the part 25 while the part 25 is being raised and lowered and its upper end portion moved back and forth by the lever 20.
- 45 The inner end portion of the pin 27 enters the groove 16 in the sleeve 15 and it is adapted to engage the bottom of the flange 17 and raise and lower the whirl disc 14 when the pin 27 is raised and lowered. When the lever 20 is in the normal position, the free inner end portion of the pin 27 50 rests within the groove 16 in spaced relation to the top and bottom walls thereof and the whirl disc 14 is in engagement with and supported by the leather covering 18 of the driving wheel 19 and the disc 14 is thus permitted to rise and fall in accordance with the irregularities of the surface of the leather covering 18 of the driving wheel 19 while the disc 14 is being rotated thereby.
- 55 When the lever 20 is moved from the position shown by full lines to the position shown by dot-and-dash lines in Figs. 1 and 2 and back again to raise and lower the pin 27, the axis of the pivot 26 moves toward and from a vertical line 30-30 which is 60 parallel to the axis of the spindle 10 and intersects the axis of the fulcrum 21 of the lever 20, and, therefore, it will be observed that the speed of movement of the pin 27 relatively to the speed of movement of the lever handle 24 is reduced as the pin 27 70 approaches the limit of its upward movement and accelerated as the pin 27 approaches the limit of its downward movement. The effect of this is to reduce the liability of breaking the yarn being fed to 75 the cone or other foundation upon the spindle 10 when the whirl disc is lowered to start the rotation of the spindle, because a very slow starting movement of the whirl disc 14 is caused by the extremely slow 80 movement of the pin 27 while it is lowering the disc 14 into engagement with the covering on the driving wheel 19 as compared with its later accelerated downward movement after the pin 27 leaves the bottom of the flange 17 to provide the clearance for the rise and fall of the disc 14 under the irregularities of the surface of the covering of the driving wheel 19.
- 85 When the lever 20 is moved from the full line to the dot-and-dash line position shown in Figs. 1 and 2, the axis of the pivot 26 not only moves toward and from the vertical line 30-30 but also back to a position beyond the same in which the lever arm 22 rests against a projection 31 on the bearing 8 forming a stop to limit the upward movement of the lever arm 23. When the lever arm 22 thus rests against the stop 31 with the axis of the pivot 26 back of the vertical line 30-30, the weight of the whirl disc 14 supported by the pin 27 will hold the lever arm 22 against the stop 31 and thus retain the whirl disc 14 raised from engagement with the covering on the driving disc 14.
- 90 Referring now to the modified construction shown in Figs. 4 and 5, 32 designates a pin which corresponds with the pin 27 shown in Figs. 1 and 2, in relation to the whirl disc 14. This pin 32 is carried by the lower end of a bar 33 which is slidable vertically in a guideway in the upper spindle bearing 8. A lever 35 is fulcrumed, at 36, on a screw which extends from the bearing 8 through a slot in the bar 33. The lever 35 corresponds in function generally with the lever 20 and it is provided with arms 37 and 38 which correspond functionally with the arms 22 and 23, respectively, of the lever 20. The upper end portion of the lever arm 37 is pivoted, at 39, to the lower end of a link 40 whose upper end is pivoted, at 41, to the upper end of the bar 33. When the lever 35 is raised to the dot-and-dash line position shown in Fig. 4, the lever arm 37 rests against a stop 42 projecting from the bearing 8, and when the lever 35 is lowered to the full line position shown in Fig. 4, the lever arm 37 rests against a stop 43 projecting from the bearing 8.
- 95 100 105 110 115 120 125 130

When the lever arm 38 is raised and lowered, the link 40 will raise and lower the bar 33 and thereby raise and lower the pin 32 in the same manner and for the same purpose 5 that the pin 27 is raised and lowered when the lever arm 23 is raised and lowered; and, when the lever arm 38 is raised and lowered, the axis of the pivot 39 moves relatively to the vertical line 5-5 corresponding with 10 the vertical line 30-30 in Fig. 1, in the same manner and for the same purpose that the axis of the pivot 26 moves relatively to the line 30-30.

I claim as my invention:—

1. In a yarn winding machine the combination of a supporting frame, a vertically arranged winding spindle journaled in the frame, a driving wheel, a whirl disc slidable longitudinally on the spindle and adapted 20 to rest normally in driving engagement with the driving wheel, means causing the spindle to rotate with the disc and permitting the disc to be raised and lowered from and into engagement with the wheel, a lever fulcrumed 25 on the frame, a part pivoted to the lever, and means operated by said part when the lever is operated to raise and lower the disc.

2. In a yarn winding machine the combination of a supporting frame, a vertically 30 arranged winding spindle journaled in the frame, a driving wheel, a whirl disc slidable longitudinally on the spindle and adapted to rest normally in driving engagement with the driving wheel, means causing the spindle 35 to rotate with the disc and permitting the disc to be raised and lowered from and into engagement with the wheel, a lever fulcrumed on the frame, a part having one end portion pivoted to the lever, means to 40 guide the other end portion of the part in a direction longitudinally of the spindle, and means associated with said part to raise and lower the disc when the lever is operated.

3. In a yarn winding machine the combination of a supporting frame, a vertically 45 arranged winding spindle journaled in the frame, a driving wheel, a whirl disc slidable longitudinally on the spindle and adapted to rest normally in driving engagement with the driving wheel, means causing the spindle 50 to rotate with the disc and permitting the disc to be raised and lowered from and into engagement with the wheel, a lever fulcrumed on the frame, a part pivoted to the lever, and means operated by said part when the lever 55 is operated to raise and lower the disc, the axis of the pivot of said part moving toward and from a line which parallels the axis of the spindle and intersects the axis of 60 the lever fulcrum to raise and lower the disc when the lever is operated.

4. In a yarn winding machine the combination of a supporting frame, a vertically 65 arranged winding spindle journaled in the frame, a driving wheel, a whirl disc slidable

longitudinally on the spindle and adapted to rest normally in driving engagement with the driving wheel, means causing the spindle to rotate with the disc and permitting the disc to be raised and lowered from and into 70 engagement with the wheel, a lever fulcrumed on the frame, a part pivoted to the lever, a part having one end portion pivoted to the lever and another end portion pivoted 75 to the lever fulcrum, respectively, and means associated with said part to raise and lower the disc when the lever is operated, said lever when operated to raise and lower the disc moving said part to move a line 80 intersecting its pivots toward and from the lever fulcrum, respectively.

5. In a yarn winding machine the combination of a supporting frame, a vertically 85 arranged winding spindle journaled in the frame, a driving wheel, a whirl disc slidable longitudinally on the spindle and adapted to rest normally in driving engagement with the driving wheel, means causing the spindle to rotate with 90 the disc and permitting the disc to be raised and lowered from and into engagement with the wheel, a lever fulcrumed on the frame, a part having one end portion pivoted to the lever and another end portion 95 pivoted to the lever fulcrum, respectively, and means associated with said part to raise and lower the disc when the lever is operated, said lever when operated to raise and lower the disc moving said part to move a line 100 intersecting its pivots toward and from the lever fulcrum, respectively, and slightly beyond the lever fulcrum when the disc is raised, and a stop to limit the movement of 105 the lever when the disc is raised.

6. In a yarn winding machine the combination of a supporting frame, a vertically 110 arranged winding spindle journaled in the frame, a driving wheel, a whirl disc slidable longitudinally on the spindle and adapted to rest normally in driving engagement with the driving wheel, means causing the spindle to rotate with the disc and permitting the disc to be raised and lowered from and into 115 engagement with the wheel, a vertically movable lever fulcrumed on the frame, a part having one portion thereof pivoted to the lever and another portion thereof guided by the frame, and means associated with said 120 part to raise and lower the disc when the lever is operated.

7. In a yarn winding machine the combination of a supporting frame, a vertically 125 arranged winding spindle journaled in the frame, a driving wheel, a whirl disc slidable longitudinally on the spindle and adapted to rest normally in driving engagement with the driving wheel, means causing the spindle to rotate with the disc and permitting the 130

disc to be raised and lowered from and into engagement with the wheel, a vertically movable lever fulcrumed on the frame and having an arm extending upwardly from its fulcrum, a part having its upper end portion pivoted to the lever arm and its lower end portion guided by the frame, and means associated with said part to raise and lower the disc when the lever is operated.

10 8. In a yarn winding machine the combination of a supporting frame, a vertically arranged winding spindle journaled in the frame, a driving wheel, a whirl disc slidably longitudinally on the spindle and adapted
15 to rest normally in driving engagement with the driving wheel, means causing the spindle to rotate with the disc and permitting the disc to be raised and lowered from and into engagement with the wheel, a vertically
20 movable lever fulcrumed on the frame and having an arm extending upwardly from its fulcrum, a part having an upper end portion pivoted to the lever arm and a lower end portion pivotally and slidably connected to
25 the frame to move longitudinally of the spindle, and means associated with the lower end portion of said part to raise and lower the disc when the lever is operated, said lever when operated to raise and lower the disc
30 moving said part to move a line intersecting its pivots toward and from the lever fulcrum, respectively.

9. In a yarn winding machine the combination of a supporting frame, a vertically arranged winding spindle journaled in the frame, a driving wheel, a whirl disc slidable longitudinally on the spindle and adapted to rest normally in driving engagement with the driving wheel, means causing the spindle

to rotate with the disc and permitting the 40
disc to be raised and lowered from and into
engagement with the wheel, a vertically
movable lever fulcrumed on the frame and
having an arm extending upwardly from
its fulcrum, a part having an upper end 45
portion pivoted to the lever arm and the
lower end portion pivotally and slidably
connected to the frame to move longitudinally
of the spindle, means associated with the
lower end portion of said part to raise and 50
lower the disc when the lever is operated,
said lever when operated to raise and lower
the disc moving said part to move a line
intersecting its pivots toward and from the
lever fulcrum, respectively, and slightly be- 55
yond the lever fulcrum when the disc is
raised, and a stop to limit the movement of
the lever when the disc is raised.

10. In a yarn winding machine the combination of a supporting frame provided with a part having a slot therein, a vertically arranged winding spindle journaled in the frame, a driving wheel, a whirl disc slidable longitudinally on the spindle and adapted to rest normally in driving engagement with the driving wheel, means causing the spindle to rotate with the disc and permitting the disc to be raised and lowered from and into engagement with the wheel, a vertically movable lever fulcrumed on the frame, a part pivoted to the lever and having a pin extending into and guided by said slot and being arranged to raise and lower the disc when the lever is operated. 60 65 70

In testimony whereof I affix my signature hereto.

ALFRED N. ALTEMUS,
